UNITED STATES PATENT OFFICE.

HARRY Y. NORWOOD, OF ROCHESTER, NEW YORK, ASSIGNOR TO TAYLOR INSTRUMENT COMPANIES, OF ROCHESTER, NEW YORK, A CORPORATION OF NEW YORK.

THERMOSTAT.

986,023.

Specification of Letters Patent.

Patented Mar. 7, 1911.

Application filed November 29, 1909. Serial No. 530,412.

To all whom it may concern:

Be it known that I, HARRY Y. Norwood, of Rochester, in the county of Monroe and State of New York, have invented certain 5 new and useful Improvements in Thermos- 10 stats; and I do hereby declare the following to be a full, clear, and exact description of the same, reference being had to the accom- 15 panying drawings, forming a part of this 20 specification, and to the reference-numerals marked thereon.

The present invention relates to thermo- 15 stats of the type in which one or more contacts are arranged to be engaged by an ex- 20 pansible conducting body such as mercury in order to establish an electrical circuit of which the expansible body forms a part, and the object of this invention is to provide for 25 securing the contacts to the casing contain- 30 ing the expansible body in such a manner that greater life to the instrument is in- 35 sured.

To these and other ends the invention re- 25 lates to certain improvements and combina- 30 tions of parts all as will be hereinafter more fully described, the novel features being 35 pointed out in the claims at the end of the specification.

In the drawings: Figure 1 is a view show- 30 ing the instrument and the means support- 35 ing the same; Fig. 2 is a detail and enlarged 40 sectional view of the instrument, and Fig. 45 3 is a section on the line *a—a* of Fig. 1.

An electric contacting thermostat is usu- 35 ally a regular mercury and glass thermome- 40 ter having platinum wires fused into the 45 glass with one end of each wire projecting 50 into the bore and into the path of the mer- 55 cury to complete the electric circuit while 60 the other end projects from the exterior of 65 the stem and has a suitable conductor se- 70 cured thereto. These platinum wires at the 75 point where they enter the glass are very 80 brittle and are easily broken, thus requiring 85 the exercise of great care in handling them 90 both during the process of manufacturing 95 as well as in use, for once they are broken 100 they cannot be repaired, and an instrument 105 thereafter has no utility for the purpose for 50 which it was designed.

In this invention a suitable casing 1, pref- 110 erably made of glass, with a bulb and a 115 bored stem as in an ordinary thermometer, 120 has fused therein one or more conductors 2,

preferably in the form of platinum wires 55 extending transversely through the stem of the casing, and each projecting at its inner end into the bore 3 thereof and at its outer end from the outer surface of the stem.

At the outer end of each conductor wire 60 is electrically connected an enlarged contact 4 which preferably is in the form of a cop- 65 per sleeve surrounding the stem in proxim- 70 ity to the conductor 2, and having the wire 75 end embedded therein. In order that this 80 contact will lie in most intimate engagement 85 with the glass and the conductor 2, the con- 90 tact is preferably deposited thereon electro- 95 platingly in accordance with any electro- 100 plating process. The glass is first coated, as 105 at 5, with a film of silver deposited from an ammoniacal solution of silver nitrate in ac- 110 cordance with well known silvering methods, 115 or with other material which will make pos- 120 sible the electrolytic deposition of copper or 125 other suitable conductor. The platinum 130 wire is by this means firmly embedded in the 135 band of copper and this band cannot be 140 shifted without breaking the glass so that 145 the platinum wire cannot break away where 150 it enters the glass. The thin film of silver 155 or other material deposited by chemical ac- 160 tion is in the most intimate contact possible 165 with the surface of the glass, conforms to 170 the most minute inequalities in its surface, 175 and is with difficulty stripped from it, and 180 the copper band when deposited by electrol- 185 ysis thereon forms a solid contact which is 190 practically indestructible. Every part of 195 the band may serve as a point of contact so 200 that the conductor wire may be easily con- 205 nected thereto in order to complete a circuit.

As a simple means for supporting the 210 thermometer and at the same time establish- 215 ing electrical connection with its contacts 4, 220 there may be provided sleeves 6 each having 225 a stem 7 projecting therefrom and passing 230 through an insulating bushing 8 in a suit- 235 able wall or support 9, said stem being se- 240 cured in the bushings in any suitable man- 245 ner as by a nut 10, and the circuit wires 11 250 being held in engagement with the nuts 10 255 by nuts 12 also fitting on the stems 7. Two 260 or more of the supporting sleeves 6 are 265 axially aligned and the thermostat stem is 270 fitted into them so that its contacts 4 lie 275 within the sleeves 6. In this position, the 280 screws 13 or other suitable devices may be

caused to frictionally engage the contacts 4 to maintain the thermometer against movement in the sleeve.

A thermostat constructed in accordance 5 with this invention has the conductors or platinum wires supported in such a manner that the breaking thereof is prevented and thus the life of the thermostat is greatly increased. The size of the thermostat contacts are also greatly increased thus permitting 10 a quicker connection of the instrument to the signaling circuit.

I claim as my invention:

1. An electrical alarm thermostat embody- 15 ing a stem of insulating material having a bore therein, an expansible conductor in the bore, a stationary conductor extending through the wall of the stem into the bore, and a contact plate or body on the exterior 20 of the stem, consisting of metal deposited upon the stem by electrolysis and having the outer end of the stationary contact embedded therein.

2. An electrical alarm thermostat embody- 25 ing a tubular stem of insulating material having a bore therein, an expansible conductor 30 in the bore, a stationary conductor extending through the wall of the stem into the bore, and an annular contact plate or body encircling the stem consisting of metal deposited upon the material thereof by electrolysis and having the outer end of the contact embedded therein.

3. An electrical alarm thermostat embody- 35 ing a stem of insulating material, an expansible conductor in the stem, a stationary conductor extending through the wall of the stem, a deposited metallic film upon the exterior 40 of the stem and the external end of the conductor, and a contact plate electrolytically deposited upon said film.

HARRY Y. NORWOOD.
